UNITED STATES PATENT OFFICE.

WILLIAM CECIL GARDINER, OF TORONTO, ONTARIO, CANADA, ASSIGNOR TO SATIN FINISH HARDWOOD FLOORING COMPANY, LIMITED, OF WESTON, ONTARIO, CANADA.

SURFACING LUMBER.

Application filed October 29, 1925. Serial No. 65,705.

The invention relates to surfacing lumber as described in the present specification and illustrated in the accompanying drawings which form part of the same.

5 The invention consists essentially of the novel features of construction pointed out broadly and specifically in the claim for novelty following a description in detail of an acceptable form of the invention.

10 The process for producing lumber of the kind herein disclosed is described and claimed in applicant's copending application Serial No. 65,706.

The objects of the invention are to produce 15 a board for floors and other surfaces that will prove impervious to moisture by a filling on the inner side and by the surface finishing on the outer side; to effect a beautiful finish on exposed surfaces; to avoid warping, coupling and heaving, and lengthen the life of the 20 boarding; to effect these purposes in an economical manner; and generally, to provide durable and efficient boarding for all kinds of surfacing.

25 In the drawings, Figure 1 is a plan view of a board showing its finished side.

Figure 2 is a plan view of a board showing its unfinished side treated.

Figure 3 is an enlarged cross sectional view 30 showing a treated flooring.

Like numerals of reference indicate corresponding parts in the various figures.

Referring to the drawings, the board 10 is 35 finished or milled on the side 11 and unfinished or rough on the side 12, and on the side

12 the filler 13 is introduced by pressure and generally applied over all the surface, so that all the pores and other interstices are filled and capped forming a positive barrier to the penetration of moisture into the board. 40

The face side 11 is treated usually after the laying of the floor with fillers, oils, varnishes or polishes, or in some cases paints, thereby insuring non-penetration of the flooring from below or above and the elimination of all 45 tendency towards warping, coupling or heaving, as well as effecting a barrier to the encroachment of vermin and all destructive agents.

The substance employed is a fluid mixture 50 of denatured alcohol, turpentine and copal gum, and it is applied under considerable pressure, so that there is no chance of a neglected part, especially in view of the fact that rollers are used to distribute the substance over the unfinished side completely 55 thereover. It has been found in many instances, that the filler is forced completely through the lumber and appears on the upper surface in the form of small beads. 60

What I claim is:

In lumber, a wooden board having finished and unfinished surfaces, said lumber containing a mixture of denatured alcohol and turpentine and copal gum extending inwardly 65 from a coating of the same in its consistent state on the unfinished surface of the board.

Signed at Toronto, Canada, this 16th day of September, 1925.

WILLIAM CECIL GARDINER.
